UNITED STATES PATENT OFFICE.

BENTON R. LYSTER AND MORTON J. LYSTER, OF WHITEFIELD, NEW HAMPSHIRE.

PROCESS FOR THE DESTRUCTIVE DISTILLATION OF WOOD.

1,157,316.

Specification of Letters Patent.

Patented Oct. 19, 1915.

Application filed December 11, 1913. Serial No. 806,061.

To all whom it may concern:

Be it known that we, BENTON R. LYSTER and MORTON J. LYSTER, citizens of the United States, residing at Whitefield, in the county of Coos and State of New Hampshire, have invented new and useful Improvements in Processes for the Destructive Distillation of Wood, of which the following is a specification.

10 In the destructive distillation of wood for the purpose of manufacturing methyl alcohol, acetate of lime, charcoal, etc., in iron or steel retorts or ovens, it is well known that there are gases evolved that do not condense 15 and that these gases are usually returned to the oven fire-box or to fire-box under boilers and burned. These incondensable gases are carbonic acid (CO_2), carbonic oxid (CO), methane (CH_4), hydrogen (H), etc. In the 20 early stages of an operation, a gas rich in carbonic acid (CO_2) and carbonic oxid (CO) is obtained. Later, as the heat is raised in the ovens or retorts, less carbonic acid (CO_2) and carbonic oxid (CO) are 25 thrown off, and the gases now evolved are richer in methane (CH_4), hydrogen (H), and acetylene (C_2H_2), ethylene (C_2H_4), etc.

Our method, broadly, contemplates utilizing part or all of the incondensable gases 30 formed during one stage or period of the operation and using them at another stage or period of the operation in a novel and desirable manner, as hereinafter more particularly described; and we have discovered, by 35 practical application of our method, that our method effects a marked increase in the yield of methyl alcohol (CH_3O), acetic acid ($C_2H_4O_2$), and a tar rich in guaiacol ($C_7H_8O_2$).

40 In the accompanying drawing, we have illustrated, as an example, a form of apparatus capable of carrying out the method of our invention; and, while our invention may be practised by other apparatus, such 45 as storing the gases in a gasometer and returning them to the ovens as desired, that given is preferred as being the simplest and most practicable.

50 In this drawing: Figure 1 is a top plan view, partly in section, of the preferred form of our apparatus; Fig. 2 is an end elevation of the apparatus; Fig. 3 is a fragmentary detail view of one of the retorts.

55 Referring now in detail to the drawing: A, B, C, D, designate a battery of retorts or ovens, usually arranged in pairs, as shown.

The retorts are in communication, by suitable connections 2, 2, 2, 2, with suitable condensers 3, 3, 3, 3, which are provided with outlets 4, emptying into a common conductor 5, which, in turn, may discharge into a suitable holder 6. Rising from each of the outlets 4 is a vertical pipe 7. The pipes 7 are in communication with a common horizontal pipe 8.

Leading from the pipe 8 are two pipes 9, 9, which are disposed between the two pairs of retorts A, B, C, and D, as shown. Carried by the pipe 8, between the points of junction therewith of the pipes 9, 9, is a valve 10. The free extremities or terminals of the pipes 9, 9 communicate with the retorts A, B, C and D. The arrangement is such that the pipes 9, 9 are crossed, one of said pipes, on one side of the valve 10, communicating with the retorts on the opposite side of the valve, and vice versa in respect to the other pipe 9; as clearly shown in the drawing.

Preferably, a steam-jet nozzle 11, in communication with each pipe 9, is utilized, to accelerate the flow of gas through the pipes 9 into the retorts.

In the operation of our apparatus, to carry out the process, constituting our invention, 85 all of the ovens or retorts are charged with wood in the usual manner; but, contrary to the usual manner, the ovens or retorts are not all run off at the same time, as for example, in a four oven plant, ovens numbered 90 A and B are charged with wood and the usual firing under these ovens is applied. Ovens C and D are charged with wood—same as A and B—but from twelve to eighteen hours later than ovens A and B, and 95 fired in usual way.

If a gas holder or gasometer is used to store the incondensable gases, the retorts or ovens may be charged with wood and fired off together and at the same time.

100 With an apparatus such as illustrated the operation of our invention is carried on as follows:—The incondensable gases coming from the ovens last charged with wood are conveyed through proper pipes into the 105 ovens charged with wood twelve to eighteen hours previously, or, the incondensable gases coming from the ovens first charged with wood are conveyed into the ovens which were charged from twelve to eighteen hours later, 110 all ovens being fired as usual. The purpose of the foregoing is to bring in contact in a

heated oven the incondensable gases evolved in ovens during the first half of their operation with the gases or vapors produced or formed in other ovens during the latter part 5 of their operation. The gases, ensuing upon the process of reduction, pass into the condensers 3, 3 (to the left in Fig. 1), communicating with the corresponding pair of retorts; in these condensers, the condensable 10 vapors are condensed, and the liquor flows through the outlets 4 into the trough or conductor 5. The uncondensed vapors, however, pass up the pipes 7, 7, thence through that portion of the pipe 8 to the left hand 15 side of the valve 10, in Fig. 1, thence to the pipe 9 (that farthest to the left in Fig. 1), to the retorts or ovens (on the right-hand side of Fig. 1), where they are combined 20 with gases in these retorts or ovens and valuable products are formed.

It appears that the non-condensable gases, rich in oxygen, evolved in the earlier stage or stages of destructive distillation, are, in effect, complementary to the non-condensable 25 gases, deficient in oxygen, produced in the later stage or stages, and that, under the conditions obtaining in the retort, these constituents combine to produce additional amounts of the desired products, particularly 30 wood alcohol and acetic acid.

Briefly summarizing; by our process, the ovens are not all charged with wood at the same time. In a four-oven plant, say, two of the ovens will be charged with wood and 35 heated by external firing, as usual, and, in from twelve to eighteen hours, thereafter, the other two will be charged, and, in this manner, the operation will be continued right along; only two ovens at a time being 40 charged, and destructive distillation begun in these ovens, but all the ovens being in operation in different stages. In our process, we conduct the non-condensable gases from the freshly-charged ovens into the ovens 45 that have been operating on their charge preferably for at least twelve hours; and we continue such introduction of said non-condensable gases, as aforesaid, to the end of the carbonizing period, which is from 50 twenty-four to thirty-six hours in duration. It will thus be seen that we put the fresh, uncondensed gases into an oven or ovens in the latter part of their run. When the old charge is "off" and earlier wood is put into the 55 ovens, of course the gases coming from this fresh charge will then be piped over into the ovens that have previously sent their gases into the freshly-charged ovens, thereby supplying the said ovens to which said gases 60 are piped with fresh gases during the latter

part of their operation. In other words, for example, all the non-condensable vapors or gases thrown off from the ovens, during the first twelve hours, or fifteen hours, of the operation, are to be introduced, by our 65 process, into all the other ovens which are being run on the last twelve or fifteen hours of their charge.

The gist of our invention resides, broadly, in the admission of non-condensable gases 70 or vapors, of predetermined character, such as are evolved from retorts at one stage or period of their operation, to retorts at a different and also predetermined stage or period of operation, the gases and stages 75 selected being, in effect, complementary with respect to the formation of additional amounts of alcohol and acetic acid.

Having thus fully described our invention, what we claim as new and desire to secure 80 by Letters Patent of the United States, is:

1. The method of conducting destructive distillation of wood, which comprises distilling the charges in retorts by external heat, and introducing non-condensable gases relatively rich in oxids of carbon, produced by one retort or set of retorts during a relatively early stage of distillation, into a retort or set of retorts during the progress 85 thereof of a relatively later stage of distillation which would ordinarily be characterized by the production of non-condensable gases relatively rich in hydrocarbons, whereby additional amounts of the desired products are formed. 95

2. The method of conducting destructive distillation of wood, which comprises introducing charges into a plurality of retorts and externally firing the several retorts so as to effect destructive distillation of the 100 charges, operations being so conducted that the different retorts or sets of retorts are a substantial stage apart in the distilling process, and introducing into each retort or set of retorts, after the termination of an early 105 stage of distillation therein and during the progress of a further stage, non-condensable gases given off by another retort or set of retorts then in an early stage of their run, whereby additional amounts of the desired 110 products are formed.

In testimony whereof, we have hereunto set our hands in presence of two subscribing witnesses.
